R. J. S. PERRY,
CLOTHES WASHING MACHINE,
APPLICATION FILED JAN. 8, 1916.

1,215,405.

Patented Feb. 13, 1917.

UNITED STATES PATENT OFFICE.

ROBERT J. S. PERRY, OF BELTON, TEXAS.

CLOTHES-WASHING MACHINE.

1,215,405.

Specification of Letters Patent. Patented Feb. 13, 1917.

Application filed January 8, 1916. Serial No. 71,081.

To all whom it may concern:

Be it known that I, ROBERT J. S. PERRY, a citizen of the United States, residing at Belton, in the county of Bell and State of Texas, have invented certain new and useful Improvements in Clothes-Washing Machines, of which the following is a specification.

My invention relates to an improvement in clothes washing machines and has for its primary object to provide a device of this class wherein a reciprocating plunger is designed to cause alternate currents of washing fluid to contact and pass through the clothes in such a manner as will effectively and positively remove dirt therefrom without injury to the fabric thereof.

Another object of the invention is to provide in a washing machine of this class, a perforate inner clothes container adapted to be disposed in spaced relation to the sides of an outer container whereby the clothes are prevented from coming in contact with the side walls of the outer container, thus providing for the circulation of a portion of the washing fluid, which is forced through the clothes, between the clothes container and the side walls of the outer container.

A further object is to provide a device of this class, which though designed to be used in connection with a heating device forming a part thereof, may also be used in connection with an ordinary stove.

With these and other objects in view, the invention consists of the construction, combination of the various parts, as will be hereinafter described and pointed out in the appended claims.

In the drawings:

Figure 1 is a view in elevation.

Fig. 2 is a vertical section on the line 2—2 of Fig. 1, looking in the direction of the arrow.

Fig. 3 is a section on the line 3—3 of Fig. 2, looking in the direction of the arrow.

Referring by numerals to the drawings, 1 indicates a lower receptacle adapted to be used as a furnace and which is provided with a door 2, an aperture 3 for the escape of smoke or fumes, and draft openings 4. The receptacle 1 supports in telescopic relation as shown at 6, an upper receptacle 5 adapted to receive a clothes containing basket 7 formed of wire mesh and disposed in spaced relation to the sides of the recep-

tacle. A rim 8 is provided at the bottom of the basket 7 for supporting the edge 9 of a perforated conical bottom 10, provided with perforations 11. A tubular member 13 is secured to the member 10 and is adapted to serve as a guide for a plunger 15. The plunger 15 comprises a tubular stem adapted to telescopically engage the tubular member 13, and a conical plunger head 16 provided with a bottom having perforations 18 and a top 19 having perforations 20.

A cover 21 is removably carried by the receptacle 5 and is provided with an aperture 22 through which is adapted to pass the upper end of the plunger 15. The aperture 22 also serves the purpose of an outlet for the steam generating within the receptacle 5. The cover 21 is further provided with handles 23.

In the upper end of the tubular stem 15 is secured an air tight closure 24 having a bifurcated end 25 pivotally secured by a pin 26 to a reciprocating lever 27. The lever 27 is pivotally secured at 28 to a post 29 secured by means of rivets 31 to the receptacle 5.

In operation the lever 27 is turned backward on its pivot 28 carrying with it the cover 21 and the plunger 15, thus providing access to the interior of the receptacle 5. The basket 7 containing articles to be washed is placed in the receptacle 5, which has previously been filled within a short distance of the top with water, to which suitable washing agents have been added, and which has been heated to the boiling point by the heating agent in receptacle 1. The lever 27 is then operated to move the plunger vertically upon the guide member 13. Upon the downward stroke of the plunger 15, the air tight closure 24 carried thereby will compress the air column formed between the bottom of the closure 24 and the surface of the washing fluid in the tubular member 13 and cause it to displace a portion of the washing fluid and force the same vertically into the clothes through the perforations 11 in the conical bottom 10 of the basket 7. The descending conical plunger head 16 will simultaneously compress the clothes against the bottom 10 and force a part of the washing fluid vertically upward, through the perforations therein, while another part of the washing fluid will be forced upwardly and outwardly through the perforated basket 7 thereby establishing an upward circulation of the washing fluid be-

2
tween the perforated basket 7 and the side walls of the receptacle 5.
Upon the upward stroke of the plunger, the air pressure, and the pressure on the 5 clothes will also be relieved, thus permitting the washing fluid to return to the same level in the tubular member 13 as before the downward stroke of the plunger head. In attaining this level it will create a downward 10 circulation through the perforations of the conical plunger head 16 and through the clothes, and also downwardly between the perforated basket 7 and the side walls of the receptacle 5, thence inwardly through the 15 sides of the basket 7 and through the clothes. It is apparent that this rapid alternate upward and downward circulation of the washing fluid through the clothes will dislodge and remove any particles of dirt from the 20 clothes without subjecting them to any undue wear or tear.

When the basket 7 containing the clothes is removed from the receptacle it will be seen that the washing fluid will be permitted to drain off through the sides of the basket and through the perforations in the bottom 10 thereof, thus obviating the necessity of coming in contact with the washing fluid when the clothes are removed from the 25 basket.

It is understood that I do not claim the exact construction shown herein but reserve the right to make such changes and alterations as will not depart from the spirit and 30 scope of the claims.

I claim:—

1. A washing machine comprising an outer receptacle adapted to contain a washing fluid, an inner clothes containing wall 40 made perforate throughout its entirety provided with a rim flange at its lower end and adapted to be fitted in the outer receptacle to rest upon the bottom thereof and to be held in slightly spaced relation from the side 45 wall, a perforated substantially conical bottom for the clothes container made of a size to be received within the carrier wall to be supported on the rim above the bottom of the outer receptacle and said bottom provided with a centrally disposed upwardly extending tubular guide, a tubular stem 50

mounted on the tubular guide to be capable of vertical reciprocatory movement, a perforated plunger head mounted on the lower end of the tubular stem provided with top 55 and bottom walls having different inclines, and means to be manually actuated to give the plunger head a reciprocatory movement toward and away from the perforated conical bottom to thus circulate the washing 60 fluid in and through the receptacles and through the perforations of the bottom and the walls of the plunger.

2. A washing machine comprising an outer receptacle adapted to contain washing 65 fluid; an inner clothes containing carrier wall formed of wire mesh made of a size to be received within the outer receptacle to rest upon the bottom thereof and to be disposed in spaced relation from the inner wall 70 of the receptacle, a rim flange provided around the lower inner edge of the carrier wall and having its upper edge raised above the bottom of the outer receptacle, a perforated bottom for the clothes containing wall 75 made of a size to be received within the wall and to rest upon the flange so that this perforated bottom is raised above the bottom of the outer receptacle, a tubular guide rigidly connected with said bottom portion substantially at the center thereof and arranged to extend vertically upwardly from the bottom, a tubular stem mounted on the tubular guide to be capable of reciprocatory movement in a vertical path, a perforated plunger head 80 rigidly mounted on the lower end of the tubular stem to thus be disposed above the perforated bottom, a cover for the outer receptacle provided with a central opening 85 through which the tubular stem is extended, and means mounted on the receptacle and connected with the extending end of the stem to be manually actuated to thus cause reciprocatory movement of the plunger with respect to the perforated bottom. 90

In testimony whereof I affix my signature in presence of two witnesses.

ROBERT J. S. PERRY.
